APPARATUS FOR PRODUCING COMBUSTIBLE GAS

Filed April 17, 1936

UNITED STATES PATENT OFFICE

2,157,487

APPARATUS FOR PRODUCING COMBUSTIBLE GAS

Arthur Holden and William A. Brown, Los Angeles, Calif., assignors to Gasolitor Co., Inc., Los Angeles, Calif., a corporation of California

Application April 17, 1936, Serial No. 74,950

3 Claims. (Cl. 261—122)

This invention relates to an apparatus for producing combustible gas, and refers particularly to an apparatus for producing a combustible gas by contact between air and a low boiling point hydrocarbon oil so as to produce a rich, substantially dry mixture of hydrocarbon vapors and air, which may be utilized in substantially the same manner as natural gas or artificial gas, such as coal or water gas.

10 It is a general object of the present invention to provide a simple and economical form of apparatus for generating a gas fuel for domestic purposes, which apparatus is especially adapted for the manufacture of gas for an individual 15 house or establishment where there is no general distribution of gas fuel.

Another object of the present invention is to provide an apparatus which is easy and simple to operate and which can produce economically 20 a gas fuel from low boiling point hydrocarbons, such as gasoline, without the danger incident to usual apparatus of this kind which require heating of the gasoline or low boiling point hydrocarbon oil to vaporize the same.

25 Another object of the present invention is to provide an apparatus capable of producing a rich mixture of vapors of a low boiling point combustible oil with air under low pressure.

Various further objects and advantages of the 30 present invention will be understood from a description of a preferred form or example of an apparatus embodying the invention, and for this purpose we have hereinbefore described a preferred form or example of an apparatus embodying the invention, the description being given with reference to the accompanying drawing, in which,

Figure 1 is an elevation mainly in vertical section.

40 Figure 2 is a section on the line 2—2 of Figure 1.

Figure 3 is an enlarged elevation, partially in section of one of the priming pipes.

45 Referring to the drawing, the apparatus there illustrated is shown as preferably comprising a vertical well 2, the lower end of which is spherically curved and provided with an opening 3, into which is fitted an inlet pipe 4 for conveying air under pressure into the apparatus. Within the well 2 and at the lower end thereof the air inlet pipe 4 is provided with a head 5 having air distributing apertures 6.

At its upper end the well 2 joins the rounded 50 bottom 7 of a main tank, which is preferably pro-

vided with slightly tapering conical side walls 8 and with a rounded head 9 at its upper end. Within the main tank there is provided a conical dividing baffle 10, the lower end of which is sealed to the rounded bottom 7 spaced somewhat from the side walls 8. The upper end of the conical dividing baffle 10 terminates in a pipe 11 passing through the head 9, and there is provided with a filling cap 12.

At the lower end of the tank and within the 10 conical baffle 10 there is provided a perforated and dished distributing baffle 13 which, on its lower end surface, is provided with a plurality of circular flanges 14 for supporting the distributing baffle above the bottom 7 of the tank. 15 Within the well 2 there is provided a plurality of priming pipes 15 which lie against the walls of the well 2 and at their lower ends are curved, as indicated at 16, to bring their ends adjacent the discharge aperture 6 in the head 3 of the 20 inlet pipe 4. At the upper end of the well the pipes 15 are bent back, as indicated at 17, to lie against the bottom 7 of the tank, and this portion of the priming pipes is split, as indicated at 18 (Fig. 3), so as to direct hydrocarbon oil into the 25 priming pipes from the tank.

The pipe 11 connecting with the upper end of the conical baffle 10 connects with a pair of diametrically opposite pipes or lines 19, which extend downwardly between the dividing baffle 10 and side walls 8 of the apparatus to the lower end thereof, at which they are connected into T portions 20 (Fig. 2), which are curved and provided at their lower end with spaced apart openings 21 for distributing gas. At the upper 30 end of the apparatus is indicated a gauge 22 and a gas fuel outlet line 23 provided with a valve 24.

35 In the operation of the apparatus herein described, the apparatus may be substantially filled with a low boiling point hydrocarbon oil, such as gasoline, through the removal of the cap 12. The pipe 4 is then connected to a source of air under low pressure, such as 4 or 5 pounds per square inch. Any suitable or usual form of apparatus for distributing air under a predetermined pressure may be connected with the pipe 4, the apparatus preferably, however, being designed to deliver air at a predetermined pressure. The gas outlet line 23 leads to different places in consumption of the gas fuel. The valve 24 may 40 be opened and the gas then will be automatically produced and withdrawn from the apparatus as it is required by the consumers through opening valves leading to burners, etc., in the usual manner.

Within the apparatus, itself, the gas fuel is generated by the air rising first upwardly through the well 2, which is maintained full of oil. In order to insure that the oil will not all be lifted 5 out of the well by the entering air the priming pipes 15 are provided for collecting the oil and bringing the oil under pressure against the discharge apertures 6 in the header 3.

The air rising upwardly in the well 2 is brought 10 into contact with oil and rises through the well until it strikes the perforated distributor plate 13, which causes the uprising mixture of air and oil to be spread out over the plate and subdivides the entering air into minute streams passing through the perforations in the plate 13. From the plate 13 the air rises upwardly under the conical dividing baffle 10, the separation of 15 the air from oil with which it is commingled being restricted because of the converging walls 20 of the dividing plate, so that within the baffle 10 a thorough contact between the air and oil is attained. At the upper end of the conical baffle 10 the admixed air and oil vapors are directed 25 downwardly through the conduits of lines 19, again being distributed in small streams at the lower end of the tank by the T heads and perforations 21 on said pipes, the air then rising 30 upwardly in contact with oil between the baffle 10 and side walls 8 to the upper end of the tank 35 where it may be withdrawn from the line 23.

By the arrangement of the apparatus shown, it has been experimentally found that a gas fuel 40 is produced which is very high in heating powers and can be passed from the line 23 over a considerable distributing distance and used in various burners or appliances in the ordinary manner of consuming gas, but the gas remains substantially dry throughout the system and the apparatus can be used continuously with little attention. One filling of the tank with oil is sufficient in order for the apparatus to produce satisfactory gas until the oil within the tank has been lowered in the space between the walls 10 and 8 and almost to the T pipes 20, after which

it is a simple matter to shut down the air supply pressure, remove the cap 21, and supply further fuel to the apparatus.

While the particular form of the apparatus herein described is well adapted to carry out the objects and advantages of the present invention, it is to be understood that various modifications and changes may be made without departing from the principles of the invention, and the invention may include all such changes and modifications as come within the scope of the claims.

We claim:

1. An apparatus for manufacturing a gas fuel from a low boiling point hydrocarbon oil, comprising an oil containing tank having a depending well of reduced size therebelow, an inlet for air into said well, priming pipes extending from the main tank with outlets for priming oil adjacent the air inlet, and means within said tank for spreading the air in the tank and contacting the same with oil therein.

2. An apparatus for manufacturing a gas fuel from a low boiling point hydrocarbon oil, which apparatus comprises an oil containing tank having a well at its lower end, an air inlet having a plurality of discharge ports at the lower end of said well, priming pipes extending down into said well from said tank discharging oil adjacent said air ports, a perforated spreader plate above said well having depending baffle members.

3. An apparatus for manufacturing a gas fuel from a low boiling point hydrocarbon oil, which apparatus comprises an oil containing tank having a well at its lower end, an air inlet having a plurality of discharge ports at the lower end of said well, priming pipes extending down into said well from said tank discharging oil adjacent said air ports, a perforated spreader plate above said well having depending baffle members, and an upwardly converging divider plate above said spreader plate.

ARTHUR HOLDEN.
